ALUMINUM MANUFACTURES, INCORPORATED, OF CLEVELAND, OHIO, A COR-
PORATION OF DELAWARE.

METAL MOLD.

1,420,903.

Specification of Letters Patent. Patented June 27, 1922.

Application filed November 22, 1920. Serial No. 425,788.

To all whom it may concern:

Be it known that I, CLAIR J. AMICK, a citizen of the United States, residing at Cleveland, in the county of Cuyahoga, State 5 of Ohio, have invented certain new and useful Improvements in Metal Molds, of which the following is a specification, reference being had therein to the accompanying drawings.

10 This invention relates to permanent molds for making hollow castings with inwardly extending projections, especially pistons for internal combustion engines. It relates in particular to multiple part cores of the general type disclosed in the patent to F. A. Parkhurst, No. 1,296,596.

One object of the invention is to provide a core for casting internal combustion engine pistons having a relatively small clearance between the inner ends of the wrist pin bosses.

Another object is to provide a core for casting internal combustion engine pistons having relatively long wrist pin bosses.

25 Another object is to provide a multiple part core, the various parts of which have contacting faces so formed as to prevent movement of the assembled parts relative to each other.

30 Another object is to provide a multiple part core for casting pistons for internal combustion engines which will withstand ordinary usage and the action of high temperatures and which may be cheaply maintained in mechanically satisfactory condition.

Other objects will be pointed out in the appended specification.

In the accompanying drawings forming a 40 part of this specification:

Fig. 1 is a top plan view of a mold for making pistons, assembled with a core constructed in accordance with my invention.

Fig. 2 is an end elevation of the mold 45 shown in Fig. 1.

Fig. 3 is a vertical section taken on line 3—3, Fig. 1 showing the core in section and the gate and mold cavities filled with metal.

Fig. 4 is a fragmentary cross section taken 50 on line 4—4, Fig. 3.

Fig. 5 is a plan view in section taken on line 5—5, Fig. 3, near the top of the core.

Fig. 6 is a similar view taken on line 6—6, Fig. 3, through the bosses of the casting.

Fig. 7 shows the order of removal of core 55 parts from the casting, the center section having been removed and the two side sections moved inward to clear the circumferentially inwardly extending projection at the open end of the casting. 60

Fig. 8 is a similar view showing the manner of removing the quarter sections of the core from beneath the bosses of the casting.

Fig. 9 is a view similar to Fig. 5 of a modified form of core. 65

In the interest of brevity and because my invention constitutes an improvement in permanent mold cores of the general class disclosed in Patent No. 1,296,596 reference is made to that patent for a detailed description of the construction and operation of the mold, the pouring gate and the means of venting the mold. These parts will be described only in sufficient detail to make clear the operation and use of the core which is 75 the subject of my invention. It will, however, be understood that while my improved form of core is capable of use with molds of the type disclosed in the above mentioned patent, it is not limited thereto since various 80 other types of molds could be employed.

Referring to the construction shown in the drawings, the body of the mold is shown as comprising a base 1 and complementary members 2 and 3 movable on the base toward 85 and from each other. These three main sections of the mold body are preferably made of cast iron.

Each of the complementary members 2 and 3 comprises an inner side wall 4, end walls 5 and 6 and top and bottom walls 7 and 8, respectively. Each of these members is also preferably formed with a series of internal webs or walls 9, 9 and 10 parallel to the end walls 5, 6. The outer side of each 95 of the complementary members is formed by a plate 11 bolted to the casting. Handles 12, 12 are secured to plates 11, 11 so that the side members of the mold can conveniently be moved to and from the operative 100 position on the base.

The inner side walls 4 of the complementary members of the mold body mutually engage when said members are moved

together, as shown in Fig. 1. Each wall 4 is formed between its ends with a semi cylindrical portion 4^a and the lower parts of these semi cylindrical walls 4^a form the outer 5 side wall of the mold cavity, the bottom of said cavity being formed by the upper face of the base 1. The upper face of the base 1 is formed with a central depression 1^b which provides for a "work spot" on the head of 10 the piston casting.

At 1^a the base 1 is provided with a circular shoulder and the bottom walls 8, 8 of the side members 2 and 3 are recessed at 8^a to receive the shoulder 1^a whereby the mold 15 members 2, 3 are properly aligned relatively to each other and also centered on the base plate. Supplemental means for alining the side members of the mold may be employed if desired, such for example, as pins 13 which 20 extend upward from the base 1 to be engaged by recesses 4^b formed in the walls 4 of the side members of the mold.

Above the mold cavity proper semi-circular walls 4^a are recessed to receive inserts 25 14, 14 which are rigidly secured to the mold members 2, 3 by screws 15 as indicated in Fig. 5. These inserts, which are provided with surface grooves 14^a, 14^b, 14^c and 14^d for the purpose of venting the mold cavity are 30 preferably arranged to form the top wall of said cavity as indicated in Fig. 3.

At 16 are devices for locking the mold members 2 and 3 together in operative position on the base.

35 The main core of the mold which is designated as an entirety by the numeral 17, is preferably made of steel and comprises in the preferred construction shown, three middle sections, 17^a, 17^b, and 17^c which are 40 arranged in a row extending, in the upper part of the core, from one side to the other of the cylindrical space between the upper parts of the walls 4^a, i. e. the parts occupied by the inserts 14, (Fig. 5). The spaces 45 at the two sides of the middle sections 17^a, 17^b, 17^c are occupied by two pairs of sections, 17^d, 17^d, which for convenience, I will call quarter sections.

In present practice with the cores of this 50 type as shown by the above mentioned patent, the interior section is substantially rectangular in horizontal cross section, having four plane faces. The interior section of my improved core which, in outline, has a 55 substantially rectangular, horizontal cross section, is however provided with a longitudinal depression in each face. The faces of the opposite narrow sides or edges of the section 17^b have substantially V shaped de- 60 pressions formed therein. Each depression provides two laterally inclined inwardly extending surfaces 18^a and 18^b uniting to form one wide V shaped surface. Two exterior sections each having their inner surfaces 65 19^a and 19^b shaped to conform to these V

shaped surfaces, closely engage with the interior section throughout the lengths of their adjacent faces.

The two remaining faces of the interior section namely the wide side faces also have 70 depressions formed therein which provide two outer surfaces 20^a, two laterally and inwardly inclined surfaces 20^b and an inner surface 20^c, the surfaces 20^b being interposed between and joining surfaces 20^a and 20^c. 75 A pair of quarter sections 17^d are suitably formed and adapted to engage with each of the side faces of the interior section so that the sections will lie in close fitting engagement therewith when assembled.

80 By reason of the V shaped contact between the two exterior sections and the interior section of the middle row of sections, lateral movement of these sections relative to one another is prevented when the core is assembled in the mold. Movement of the interior section relative to the pairs of quarter sections is similarly prevented by the substantially beveled surface contact between the sections. Any tendency of the 85 middle row of sections to tilt from a vertical position in the mold due to a wearing away of the inserts is thus effectively resisted by the laterally inclined surfaces 20^c which engage the quarter sections, even 90 though the insert has worn considerably. By reason of the shape and arrangement of the contacting surfaces between the sections of the core, the sections are easily held in assembled relation and are prevented 95 from movement relative to each other with the result that the core becomes practically a unitary structure.

100 The core surfaces which are located below the inserts 14 and which form the inner side and bottom walls of the mold cavity proper are provided with various depressions to give the desired contour to the interior of the piston casting. As indicated in 105 Figs. 6 and 7 the quarter sections of each pair 110 are shaped with the recess, *a*, to form the wrist pin bosses of the piston casting, one-half of the recess being formed in each quarter section of the core. It will be noted that the 115 boss recesses, *a*, in each pair of sections extend so deeply into the sections that the inner end walls, *a'*, lie within the cross sectional outline of the interior section. That is, a plane joining the two surfaces 20^a on one side of the interior section would cut across 120 recess, *a*, the end wall, *a'*, falling within the interior sections as thus outlined. In other words the boss recesses, *a*, extend into the depressions in the interior section and the bosses formed in the recesses are thus relatively very long as 125 compared with those formed in recesses which extend only to the surface of the interior section as has been the practice heretofore. Furthermore it will be noted that rela- 130

tively small space is provided between the inner end of the boss recesses due to the present formation of the core sections, as compared with present practice, the result being that pistons may be cast with a smaller clearance between the inner ends of the wrist pin bosses than at present.

The construction of the sections 17^a permits these sections to be moved laterally 10 apart and disengaged from the bosses of the casting.

In the construction shown the adjacent faces of the core sections 17^a are recessed at b, c to form strengthening ribs between 15 the pin bosses and the side walls of the piston, and at their lower ends each pair of quarter sections is recessed at d and the interior middle section 17^a is recessed at e, said recesses d, e providing for a strengthening and heat dissipating rib on the inner side of the piston head in a plane parallel to the axis of the pin bosses and in line with the ribs formed by the recesses b, c.

At its lower ends the core is of reduced 25 diameter at 17^e to make the side wall of the piston casting adjacent the head of ample thickness to accommodate packing rings. And between the recesses, a, for the piston pin bosses and the upper end of the mold 30 cavity, the core is formed with a circumferential depression, f, to provide an internal flange on the skirted piston near the open end thereof for the double purpose of strengthening and stiffening the lower end 35 of the piston and providing space for a wiping ring.

It is exceedingly important that the core sections be rigidly and accurately supported in relation to each other and in relation to 40 the body of the mold and I have made provision to this end. The dimensions of the cross sections are such that when assembled the core snugly fits the cylindrical wall formed by the inserts 14 of the mold body. 45 In addition the core sections 17^a, 17^c are formed with outwardly turned flanges 18 which rest upon the top walls 7 of the mold body to limit the downward movement of said core sections, and the sections 17^a are 50 provided with outwardly turned flanges 19 for a similar purpose. Also the interior core section 17^b is formed with the shoulders 20 which engage the upper ends of sections 17^a and 17^c. The section 17^b is also formed 55 with flanges 21 which are adapted to be engaged by a tool to facilitate the loosening of the central section when the core is withdrawn from the mold.

To insure the accurate positioning of the 60 core circumferentially a key 22 is suitably secured as by screws 23 to an insert 14 and located so that it will engage each of a pair of quarter sections, the meeting faces of the quarter sections being cut away to 65 form a key way 22^a for engagement with key

22 (Figs. 3, 4 and 5). No additional positioning means is necessary since, due to the cross sectional configuration of the core sections the sections are held in close assembled relation in the mold as noted above. The 70 middle core sections 17^a, 17^c are tapered on two sides toward their lower ends, the section 17^b is similarly tapered on all four sides and the respective sections are nicely fitted in their faces to each other and on 75 their outer curvilinear faces to the mold walls 4^a so that when the core is assembled in the mold body it is both accurately positioned and rigidly supported.

To facilitate the handling of the core 80 parts the middle sections 17^a, 17^b, 17^c are provided with handles 27, 28, 29 respectively, and the quarter sections 17^a, are provided with handles 30.

For the purpose of coring out the pin 85 bosses of the piston casting, a core pin 31, preferably of steel, is removably mounted in each of the mold sections 2 and 3 so as to project into the pin boss cavity. A steel 90 wearing sleeve 32 is preferably provided for each of the pins, the pin and the bore of the sleeve being correspondingly tapered to insure a snug fit and the length of the pin being such that its inner end engages the metal of the quarter core sections as 95 indicated in Figs. 4, 6, and 7.

The body of the mold may be formed or provided with any suitable form of gate for the introduction of the molten metal into the mold cavity.

To facilitate the escape of air and gases from the mold, special venting means may be and preferably are provided. In the construction shown the inserts 14 are formed with grooves 14^a on their inner faces, with 100 grooves 14^b on their outer faces and with grooves 14^c, and 14^d on their top and bottom faces, respectively. These grooves insure the escape of air or gases which find their way to the top of said mold cavity. Also 110 the base 1 may be bored out centrally to receive a plug 34 which is provided with flats or grooves on its outer surfaces which constitute passages for the escape of air or gases downward through the base.

I have also formed grooves 35, and 36 in one or both of the adjacent faces of each pair of quarter sections, as shown in Fig. 4. Air or gases rising in the rib recesses, e, escape upward through the grooves 35 into 120 the boss recesses, a, and thence through grooves 36 into grooves 14^a, 14^b and 14^c.

In the interest of clearance the size of the venting grooves or passages is exaggerated as shown in the drawings, as will readily be understood by those skilled in the permanent mold art.

In assembling the core and mold herein described the side members 2 and 3 are moved together into operative position on 130

the base 1. Next the quarter sections 17^a are lowered into approximately the positions they should occupy, the pair of sections having key way 22^a engaging with key 22; then sections 17^a and 17^c are inserted between the pairs of quarter sections and finally interior section 17^b is inserted so as to accurately position all of the sections. When the side members 2 and 3 are clamped together by locking means 16, the core sections are held in close contact with one another and constitute practically a rigid unitary structure. The core pins are next inserted and the molten metal poured into the mold cavity. After the casting has solidified sufficiently the core pins are first removed, then the interior section 17^b of the main core is removed by withdrawing it axially or longitudinally upward. Then the inside metal core sections 17^a and 17^c are moved laterally inward, the necessary clearance being afforded by the upward movement, and preferably entire removal of the section 17^b, and when they have cleared the internal flange D of the casting, as shown in Fig. 7; they are drawn longitudinally upward and out of the mold. Next, by grasping the handles 30 of one pair of the quarter sections, said sections are swung laterally into the position indicated for one of said sections in Fig. 8. In this view the quarter section is clear of the pin boss but not of circumferential flange D of the casting. However, by tipping the upper end of the section radially inward it is made to clear the flange D, whereupon it can be withdrawn longitudinally from the mold. The first pair of quarter sections are thus withdrawn simultaneously, or nearly so, and thereupon the second pair can be freely swung laterally clear of the adjacent boss A of the casting and then withdrawn longitudinally from the mold.

After the removal of the core 17 the mold members 2 and 3 are unlocked and drawn apart far enough to permit the casting to be withdrawn, whereupon they are again moved into engagement with each other, locked and the operation repeated.

In Fig. 9, a modified form of core is shown. It resembles the preferred form of core in all respects except in the configuration of the contacting surfaces, of the interior and exterior sections. The surfaces 48 and 49 of the interior section 47^b are substantially concave. The pairs of quarter sections 47^a are shaped with substantially convex surfaces 50 for engagement with the corresponding surfaces 48 of the interior section 47^b. The exterior sections 47^a and 47^c are also provided with substantially convex surfaces 51 for engagement with surfaces 49 of the interior section. Due to the nature and shape of the contacting surfaces

of the core sections, the assembled core parts 65 may be easily held in assembled relation in the mold and movement relative to one another prevented as described above in connection with the preferred form of construction.

The assembled core is positioned in the mold by a key 53 secured to the adjacent insert and a key way 53^a formed in the meeting faces of a pair of quarter sections 47^a in a manner similar to that described 75 above.

It will be seen that I have provided a multiple part core with the parts so shaped that they may be firmly and rigidly held in assembled relation and accurately positioned 80 in a mold. The pair of quarter sections which have interlocking engagement with the mold body act to position the assembled core accurately in the mold. The several parts of the middle row of sections are prevented from lateral movement relative to each other by the nature of the contacting faces while the middle row of sections is prevented from lateral movement relative 85 to the pairs of quarter sections by reason of the shape of the contacting faces. The various sections, therefore, comprise a structure which is capable of being easily held in assembled relation as a practically unitary structure.

Furthermore, by reason of the relatively thin interior section, correspondingly deep boss recesses in the quarter sections make possible inwardly extending projections on the castings which are longer in relation to the diameter of the casting than have been made heretofore in permanent molds and which also have a smaller clearance between the inner ends thereof than heretofore.

In casting high melting point metals, such as aluminum alloys, edges and corners of core sections when exposed to the action of the molten metal have a tendency to wear away quickly. My improved form of core eliminates much of the trouble arising from 105 this cause. In multiple part cores of this general type in which any section or sections for instance the middle row of sections, may move or tilt relative to the remaining sections, corners and edges at the end of the 110 sections will be directly exposed to contact with the molten metal. Such contact results in a short life of the core and in necessarily high maintenance costs.

In my core, however, no movement of the 120 various parts is possible and it therefore is not subject to such excessive wear and the high maintenance costs incident thereto.

It is to be understood that the construction of my improved core can be varied widely 125 without departing from my invention, and that the specific form of construction disclosed has been shown simply for the pur-

pose of explanation and illustration, the scope of the invention being defined by what is claimed.

What is claimed:

- 5 1. In a permanent mold for casting pistons the combination with a permanent mold body having a cavity open at one end and adapted to form the outer head and side walls of a piston casting and having a gate 10 through which molten metal can be introduced into the cavity, of a permanent core supported on the mold body within a surrounding wall thereof and extending into the cavity of the mold to form the inner head and side walls of the piston casting, said core comprising an interior section having wide edge portions and a relatively thin central portion formed by longitudinally extending depressions in opposite sides of the 15 said section, and a plurality of exterior sections surrounding the said interior section, pairs of the exterior sections having longitudinally extending enlarged portions adapted to seat in the said depressions in the interior sections, each pair of exterior sections having a wrist pin boss recess extending inwardly into said enlarged portions thereof whereby a piston having relatively small clearance between the inner ends of the wrist 20 pin bosses may be cast, another pair of the said exterior sections disposed at the end sides of the said interior section being inwardly shiftable upon removal of the said interior section. 25

30 2. In a permanent mold for casting pistons the combination with a permanent mold body having a cavity open at one end and adapted to form the outer head and side walls, of a piston casting and having a gate through which molten metal can be introduced into the cavity, of a permanent core supported on the mold body within a surrounding wall thereof and extending into the cavity of the mold to form the inner head and side walls of the piston casting, said core comprising an interior section having a plurality of side surfaces each formed with a longitudinally extending depression, and a plurality of exterior sections surrounding 40 the interior section, each exterior section having a surface conformable to and adapted to engage with an adjacent surface of the said interior section whereby the said sections are prevented from movement relative 45 to each other when in assembled position. 50

55 3. In a permanent mold for casting pistons the combination with a permanent mold body having a cavity open at one end and adapted to form the outer head and side walls of a piston casting and having a gate through which molten metal can be introduced into the cavity, of a permanent core supported on the mold body within a surrounding wall thereof and extending into the cavity of the mold to form the inner head and 60

65 4. In a permanent mold for casting pistons the combination with a permanent mold body having a cavity open at one end and adapted to form the outer head and side walls of a piston casting and having a gate through which molten metal can be introduced into the cavity, of a permanent core supported on the mold body within a surrounding wall thereof and extending into the cavity of the mold to form the inner head and side walls of the piston casting, said core comprising an interior section having edge surfaces and side surfaces, the said side surfaces consisting of a plurality of laterally inclined surfaces formed by longitudinally extending depressions, and a plurality of exterior sections surrounding the interior section, each exterior section having laterally inclined surfaces conformable to and adapted to engage with the surfaces of the interior section whereby movement of the sections relative to each other is prevented when the sections are in assembled position. 90

5. In a permanent mold for casting pistons the combination with a permanent mold body having a cavity open at one end and adapted to form the outer head and side walls, of a piston casting and having a gate through which molten metal can be introduced into the cavity, of a permanent core supported on the mold body within a surrounding wall thereof and extending into the cavity of the mold to form the inner head and side walls of the piston casting, said core comprising an interior section having edge surfaces and side surfaces, each surface consisting of a plurality of laterally inclined surfaces formed by a longitudinally extending depression, and a plurality of exterior sections surrounding the interior section, each exterior section having laterally inclined surfaces conformable to and adapted to engage with the surfaces of the interior section whereby movement of the sections relative to each other is prevented when the sections are in assembled position. 100

6. In a permanent mold for skirted piston castings, the combination with a permanent mold body having a cavity open at one end and adapted to form the outer head and side walls of the piston casting and having a gate through which molten metal can be introduced into the cavity, of a permanent, sectional core supported on the mold body 110

115

120

125

130

- within a surrounding wall thereof and extending into the cavity of the mold to form the inner head and side walls of the piston casting, said core having its outer surface 5 formed with cavities to form a pair of pin bosses on the inner side walls of the piston casting and with a circumferential depression arranged to form an inwardly extending circumferential flange on the inner side 10 walls of the piston casting, the said core also having a series of more than two sections arranged in a row across the mold cavity with two of them engaging the inner side wall of the casting and the said core 15 supporting wall of the mold body at opposite points, and the core having also sections arranged on opposite sides of said row of sections to engage the inner side wall of the casting, the sections at one side of the said 20 row of sections having interlocking engagement with the mold body, the several sections being formed and arranged so that the said interior section when moved endwise affords clearance to permit the outer sections 25 of the core to be successively moved laterally out of engagement with the pin bosses and the inwardly extending flange of the piston casting and then endwise out of the said casting.
- 30 7. In a permanent mold for casting pistons the combination with a permanent mold body having a cavity open at one end and adapted to form the outer head and side walls of the piston casting and having a 35 gate through which molten metal can be introduced into the cavity, of a permanent core supported on the mold body within a surrounding wall thereof and extending into the cavity of the mold to form the inner 40 head and side walls of the piston casting, said core comprising an interior section having wide edge portions and a relatively thin central portion formed by longitudinally extending depressions in the opposite sides of 45 the said section, and a plurality of exterior sections surrounding the said interior section, the sections on one side of the said interior section having interlocking engagement with the mold body, and pairs of the 50 exterior sections having longitudinally extending enlarged portions adapted to seat in the said depressions in the interior section, each pair of exterior sections having wrist pin boss recesses extending inwardly 55 into the said enlarged portions thereof, whereby a piston having an inwardly extending annular projection adjacent its open end and having a relatively small clearance between the inner ends of the wrist pin 60 bosses may be cast.
8. A collapsible core for a cup-shaped article having inwardly extending projections the inner ends of which are separated by a relatively small space and also having an

annular inwardly extending projection, comprising an interior section substantially rectangular in cross section and provided with a longitudinally extending depression in each side face thereof, and a plurality of exterior sections surrounding the interior section each exterior section having longitudinally extending raised portions conformable to and adapted to seat in the said depressions when the core sections are in assembled position.

9. A collapsible mold core for forming the inner walls of an internal combustion engine piston having inwardly extending wrist pin bosses, the inner ends of said bosses being separated by a relatively small space, said piston inner walls having an annular inwardly extending projection between the said bosses, and the open end of the said piston, said core comprising an interior section having four vertical side faces, an opposite pair of said faces, adjacent the bosses, being provided with a longitudinally extending depression, and a plurality of exterior sections surrounding the interior section, the exterior sections adjacent the bosses having longitudinally extending projections conformable to and adapted to seat in the said depressions of the interior section when the core sections are in assembled position, a pair of other exterior sections being positioned in contact with the other pair of interior core vertical faces, said last named pair of exterior sections being inwardly shiftable when said interior section is removed, to permit the sequential removal of said last 100 named and the said first named pair of exterior sections.

10. A collapsible core for an internal combustion engine piston having inwardly extending wrist pin bosses, the inner ends of which are separated by a relatively small space, and also having an annular inwardly extending projection between the said bosses and the open end of the said article, comprising an interior section substantially rectangular in cross section and provided with a longitudinally extending depression in the opposite side faces thereof adjacent the said bosses, and a plurality of exterior sections surrounding the interior section, the exterior sections adjacent the bosses having longitudinally extending raised portions conformable to and adapted to seat in the said depressions of the interior section when the core sections are in assembled position, another pair of exterior sections adjacent the other side faces of the said interior section, being inwardly shiftable upon removal of the said interior section.

In testimony whereof, I hereunto affix my 125 signature.

CLAIR J. AMICK.
